Primary Examiner — Ian Simmons*Assistant Examiner* — Richelle Shelton(74) *Attorney, Agent, or Firm* — Hayes Soloway P.C.(57) **CLAIM**

The ornamental design for a airway device cap and strap holder, as shown and described.

DESCRIPTION

FIG. 1 is a front view of the airway device cap and strap holder, showing our new design;

FIG. 2 is a rear elevational view thereof;

FIG. 3 is a side elevational view thereof, the opposite side being a mirror image thereof;

FIG. 4 is a top plan view thereof;

FIG. 5 is a top perspective view thereof; and,

FIG. 6 is a bottom perspective view thereof.

1 Claim, 3 Drawing Sheets(56)
